Specification for Design.

Patented Oct. 20, 1914.

Application filed September 4, 1914. Serial No. 860,294. Term of patent 3½ years.

To all whom it may concern:

Be it known that I, CHARLES B. OTT, a citizen of the United States, residing at Woodlawn, in the county of Ohio and State of West Virginia, have invented a new, original, and ornamental Design for Artificial-Light Inclosures, of which the following is a specification, reference being had to the accompanying drawing, forming part thereof.

Figure 1 is a top plan view of an artificial light inclosure, showing my new design; and Fig. 2 is a side elevation of the same.

I claim:

The ornamental design for an artificial light inclosure, as shown.

CHARLES B. OTT.
